SYNCHRONISM INDICATING AND CONTROL SYSTEM

Ralph N. Stoddard, Pittsburgh, Pa., assignor to Westinghouse Electric and Manufacturing Company, a corporation of Pennsylvania

Original application April 15, 1932, Serial No. 605,546. Divided and this application May 22, 1937, Serial No. 144,175

7 Claims. (Cl. 171—118)

This is a divisional application of my application Serial No. 605,546, filed April 15, 1932, which has matured into Patent No. 2,081,684, dated May 25, 1937.

5 My invention relates, generally, to control systems and, more particularly, to synchronism indicating and control systems.

10 The object of the invention generally stated is to provide a synchronism indicating and control system which shall be of simple construction, reliable, accurate and efficient in operation and which may be readily and economically manufactured and installed.

15 A more specific object of the invention is to provide for indicating the degree of synchronism between two alternating current power lines or systems at a point remote from the place where the indication is originated and for causing the systems to be connected from the remote point 20 all over a single control and signalling circuit.

25 Another object of the invention is to provide for indicating at a remote point the degree of synchronism between two alternating current power lines or systems controlling the operation 30 of the connecting breaker and indicating its position over a single signalling channel.

35 A further object of the invention is to provide for indicating the degree of synchronism, closing the connecting breaker and indicating the position of the breaker over a single signalling channel by means of oscillation generators and receivers operating at different frequencies.

These and other objects of the invention will 40 become more apparent from a study of the following detailed description in conjunction with the drawing in which the single figure is a diagrammatic view of a system embodying the principal features of the invention.

45 Referring now to the drawing, the system there shown is arranged to transmit an indication of the degree of synchronism between two portions of a power system to a remote point and to control and supervise the operation of a circuit breaker from the remote point for connecting the two portions of the power system together. The two portions of the power system are represented by conductors 41 and 42 which are to be connected together by means of a circuit breaker, shown generally at 43. The circuit breaker 43 is provided with the usual closing solenoid 44 and tripping solenoid 45, both of which are controlled by an actuating relay 46.

50 In order to indicate the degree of synchronism between the two portions of the system so that an operator may be informed of the proper time

to close the circuit breaker 43, potential transformers 47 and 48 are connected as shown, to the conductors 41 and 42, respectively, and to the double primary winding of a grid transformer 49 the secondary winding of which is connected in 5 the grid circuit of a vacuum tube 50. The plate circuit of the vacuum tube 50 is connected to an insulating transformer 52 which is connected to the single control and signalling circuit represented by the conductors 22. It will be observed that, with this circuit arrangement, the frequencies of both portions of the power systems 10 will be applied to the control and signaling circuit 22.

15 While the transformer 49 is shown and described as having a double primary winding and a single secondary winding, it will be readily apparent that two separate transformers may be used having the primary windings connected as shown in the drawing and the secondary windings connected in series circuit relation.

20 An amplifier shown generally at 53 is connected to the control and signalling circuit and has connected in its output circuit a filter circuit, shown generally at 54.

25 The amplifier 53 is of well-known construction comprising a second insulating transformer 24 for connecting the signalling circuit 22 to the grid circuit of a three-electrode vacuum tube 25 and a plate transformer 26, connected as shown 30 in the plate circuit of the vacuum tube 25. The entire output of the amplifier 53 is then applied through the plate transformer 26 to the filter circuit 54.

35 The filter circuit 54 comprises an inductance coil 29 and a variable condenser 30 which are connected in series circuit relation across the secondary of the plate transformer 26. As will be readily understood, the condenser 30 may be adjusted so that only a predetermined frequency 40 is permitted to traverse the filter circuit 54 while all other frequencies are excluded therefrom.

45 In this instance, the variable condenser 30 in filter circuit 54 is adjusted to tune it to the frequency of the power systems. This particular frequency is then applied to a synchronization indicator, shown generally at 55, which comprises a three-electrode vacuum tube 56 having its grid circuit connected to the filter circuit 54, as illustrated, and its plate circuit connected 50 to an indicating meter 57.

55 The indicating meter 57 may be of any suitable type which will indicate either a maximum scale deflection or a zero scale deflection when the frequency of the two portions of the power system 55

are in synchronism. It is apparent that this system of synchronizing corresponds generally to the bright and dark lamp methods of synchronizing which are well known in the art.

5 A switch 53 is provided in the grid circuit of the vacuum tube 56 in order to disconnect it from the filter circuit 54 when the synchronization indicator 55 is not in use.

With a view to providing for closing the circuit 10 breaker 43 when synchronism is indicated between the two portions of the power system, an oscillation generator, shown generally at 60, is connected to the control and signalling conductors 22 through a transformer 21, as shown.

15 The oscillation generator 60 is of well-known construction and comprises an inductance coil 11 connected in the plate circuit of a three-electrode vacuum tube 12 and a variable condenser 13 by means of which the frequency of oscillation of 20 the generator may be varied in the usual manner. Any suitable current source may be used for heating the filament of the vacuum tube 12 and for applying thereto the desired plate and grid potentials. The generator 60 is arranged to 25 supply oscillations of a predetermined frequency to the control and signalling circuit when a switch 61 in the grid circuit of the vacuum tube 12 of this generator is closed.

The frequency generated by the oscillation generator 60 is transmitted over the signalling channel 22 to the apparatus station to operate a receiver 63 thereat. The receiver 63 is connected to the signalling channel 22 through an amplifier 62 and filter circuit 28 similar to the amplifier 53 and filter circuit 54, respectively, at the other station.

Relay 34 is energized and operated in response to the operation of the receiver 63 to close an obvious energizing circuit for the actuating relay 46. Upon closure of relay 46, the closing coil 44 of the breaker 43 is energized to close the breaker.

In order to give an indication back to the operator that the circuit breaker 43 has closed, a supervisory relay 64 is provided and is disposed to initiate the operation of a second oscillation generator, shown generally at 65, which is connected to the control and signalling circuit, as shown, and arranged to generate a frequency different from any of the other frequencies applied to this circuit. The supervisory relay 64 is energized when contact members 43a are bridged on closure of the circuit breaker 43 and is deenergized when these contacts are opened on the tripping of the circuit breaker.

55 The oscillations produced by the generator 65 are amplified by the amplifier 53 and applied to a second filter circuit 66 which is tuned to receive only oscillations of the frequency supplied from this generator. The oscillations which are permitted to pass through the filter circuit 66 are received by a second receiver including the three-electrode vacuum tube 33, shown generally at 67, thereby causing receiving relay 34 to become energized. The energization of the receiving 60 relay 34 serves to light a red indicating lamp 68 to inform the operator that the circuit breaker 43 is closed.

It will be observed that a green light 69 will be lighted when relay 34 of the second receiver 67 is deenergized to indicate to the operator that the circuit breaker 43 is in the open position.

In describing the operation of the synchronizing system, it will be assumed that the circuit breaker 43 is in the open position. The supervisory relay 64 is deenergized and the generator

55 is not functioning. The operating switch 61 is open and, since generator 60 is not functioning, relay 34 of receiver 63 is deenergized and, as a result, actuating relay 46 is also deenergized. It will also be assumed that the filaments of all of the vacuum tubes are connected to suitable current sources and that suitable plate and grid potentials are supplied to the proper indicated connections from a suitable power source not shown.

10 The synchronizing switch 58 is closed and the operator watches the movement of the pointer of the indicating meter 57. When it has reached the predetermined point along the scale where synchronism is indicated between the two portions of the system, the operator closes switch 61 thereby initiating the operation of generator 60 and the receiving relay 34 of the receiver 63 is in turn energized. As set forth hereinbefore, the energization of relay 34 of receiver 63, causes the 15 energization of actuating relay 46 which serves to complete a circuit for energizing the closing coil 44 to operate the circuit breaker 43 to the closed position.

Upon the closure of the circuit breaker, supervising relay 64 is energized thereby causing generator 65 to function and operate the receiver 67 to indicate, by lighting red signal lamp 68, that the circuit breaker 43 is closed.

20 When it is desired to open the circuit breaker 43, the operator opens operating switch 61 thereby arresting the functioning of generator 60 and, as a result, deenergizing relay 34 of the receiver 63. Actuating relay 46 is immediately deenergized and completes a circuit for energizing the trip coil 45 to effect the opening of circuit breaker 43. The supervisory relay 64 is then deenergized and the functioning of generator 65 is arrested and, as a result, relay 34 of receiver 61 is deenergized causing the red signal lamp 68 to be extinguished and the green signal lamp 69 to be 25 lit.

30 It will be readily apparent to those skilled in the art that the generator 60 may be operated only for a sufficient length of time to close the circuit breaker 43 and that it may then be deenergized. In order to trip the circuit breaker 43, with this arrangement, a second generator 35 may be provided for causing the energization of trip coil 45.

35 Since further changes may be made in the above circuits and different embodiments of the invention may be made without departing from the scope thereof, it is intended that all matter contained in the foregoing description or shown 40 in the accompanying drawing should be interpreted as illustrative and not in a limiting sense.

45 I claim as my invention:

1. A system for synchronizing two electrical 50 systems having applied thereto alternating currents of predetermined frequency comprising, in combination, a first station, a second station, a single circuit connecting the stations, circuit-closing means at the second station for connecting the electrical systems together, transmitting vacuum tube means at the second station responsive to the frequencies of the systems for applying said frequencies to the single circuit connecting the stations, receiving vacuum tube means at the first station for receiving the frequencies from the single circuit, indicating means connected to the receiving means to indicate the degree of synchronism between the systems, and control and supervision means connected to the circuit at the first station to actuate the circuit 55 60 65 70 75 80 85 90

closing means at the second station and indicate the position thereof.

2. A system for synchronizing two electrical systems having applied thereto alternating currents of predetermined frequency comprising, in combination, a first station, a second station, a single circuit connecting the stations, circuit closing means at the second station for connecting the electrical systems together, transmitting vacuum tube means at the second station responsive to the frequencies of the systems for applying said frequencies to the circuit connecting the stations, receiving vacuum tube means at the first station for receiving the frequencies from the single circuit connecting the stations, indicating means connected to the receiving means to indicate the degree of synchronism between the systems, and means at the first station for applying a control frequency to the circuit to actuate the circuit closing means at the second station.

3. A system for synchronizing two electrical systems having applied thereto alternating currents of predetermined frequency comprising, in combination, a first station, a second station, a single circuit connecting the stations, transmitting vacuum tube means at the second station responsive to the frequencies of the system for applying said frequencies to the circuit connecting the stations, receiving vacuum tube means at the first station for receiving the frequencies from the circuit, indicating means connected to the receiving means to indicate the degree of synchronism between the systems, a circuit breaker at the second station for connecting the systems together, an actuating relay for controlling the operation of the circuit breaker, a generator at the first station for applying oscillations of a predetermined frequency to the circuit, amplifying means at the second station for amplifying the oscillations applied to the circuit by the generator, receiving means connected to the amplifying means and responsive only to the frequency of said generator, a relay actuated by the receiving means on application of oscillations thereto from the generator at the first station to control the operation of the actuating relay, a generator at the second station for applying oscillations of a predetermined frequency to the circuit, a relay energized on closure of the circuit breaker for initiating the functioning of the generator at the second station, receiving means at the first station connected to the circuit and responsive only to the frequency applied thereto by the generator at the second station, a relay actuated by the receiving means at the first station, and signalling means controlled by the last named relay for indicating at the first station the position of the circuit breaker.

4. A system for synchronizing from a first station two electrical systems at a second station having applied thereto alternating currents of predetermined frequency comprising, in combination, a circuit breaker for connecting the said systems together, a single circuit connecting the stations, transmitting vacuum tube means at the second station responsive to the frequencies of the systems for applying them to the single circuit, receiving vacuum tube means at the first station for receiving the frequencies transmitted over the single circuit, indicating means connected to the receiving means to indicate the degree of synchronism between the systems and means including a vacuum tube transmitting means at the first station and a vacuum tube

receiving means at the second station for controlling over said single circuit the operation of the circuit breaker at the second station.

5. A system for synchronizing two electrical systems having applied thereto alternating currents of predetermined frequency comprising, in combination, a first station, a second station, a single circuit connecting the stations, circuit closing means at the second station for connecting the electrical systems together, transmitting vacuum tube means at the second station responsive to the frequencies of the systems for applying said frequencies to the single circuit connecting the stations, receiving vacuum tube means at the first station for receiving the frequencies from the single circuit, indicating means connected to the receiving means to indicate the degree of synchronism between the systems, transmitting means at the first station operable to apply a predetermined frequency to the single circuit, receiving means at the second station responsive to said predetermined frequency, and means controlled by the receiving means for controlling the operation of the circuit closing means.

6. A system for synchronizing two electrical systems having applied thereto alternating currents of predetermined frequency comprising, in combination, a first station, a second station, a single circuit connecting the stations, circuit closing means at the second station for connecting the electrical systems together, electronic transmitting means at the second station responsive to the frequencies of the systems for applying said frequencies to the circuit connecting the stations, electronic receiving means at the first station for receiving the frequencies from the single circuit connecting the stations, indicating means connected to the receiving means to indicate the degree of synchronism between the systems, electronic transmitting means at the second station for applying an indicating frequency to the single circuit, electronic receiving means at the first station responsive to said indicating frequency operable to indicate the position of the circuit closing means at the second station.

7. A system for synchronizing two electrical systems having applied thereto alternating currents of predetermined frequency comprising, in combination, a first station, a second station, a single circuit connecting the stations, transmitting vacuum tube means at the second station responsive to the frequencies of the systems for applying said frequencies to the single circuit connecting the stations, amplifying means at the first station for amplifying the frequencies applied to the single circuit, receiving vacuum tube means at the first station connected to the amplifying means thereat for receiving the said frequencies from the circuit, indicating means connected to the receiving means to indicate the degree of synchronism between the systems, a circuit breaker at the second station for connecting the systems together, an actuating relay for controlling the operation of the circuit breaker, a generator at the first station for applying oscillations of a predetermined frequency to the circuit, amplifying means at the second station for amplifying the oscillations applied to the circuit by the generator, receiving means connected to the amplifying means and responsive only to the frequency of said generator, a relay actuated by the receiving means on application of oscillations thereto from the generator at the

first station to control the operation of the actuating relay, a generator at the second station for applying oscillations of a predetermined frequency to the circuit, a relay energized on closure of the circuit breaker for initiating the functioning of the generator at the second station, additional receiving means at the first station connected to the amplifying means thereat

and responsive only to the frequency applied thereto by the generator at the second station, a relay actuated by the receiving means at the first station, and signalling means controlled by the last named relay for indicating at the first station the position of the circuit breaker. 5

RALPH N. STODDARD.
